W. E. COCHRAN,
LIGHTING FIXTURE,
APPLICATION FILED DEC. 19, 1917.

1,286,535.

Patented Dec. 3, 1918.

Wesley E. Cochran Inventor

Oscar B. Billman Attorney

UNITED STATES PATENT OFFICE.

WESLEY E. COCHRAN, OF CLEVELAND, OHIO.

LIGHTING-FIXTURE.

1,286,535.

Specification of Letters Patent.

Patented Dec. 3, 1918.

Application filed December 19, 1917. Serial No. 207,843.

To all whom it may concern:

Be it known that I, WESLEY E. COCHRAN, a citizen of the United States, residing at Cleveland, in the county of Cuyahoga and State of Ohio, have invented certain new and useful Improvements in Lighting-Fixtures, of which the following is a specification.

My invention relates to improvements in lighting fixtures, and more particularly to that class or type known as "indirect lighting" fixtures.

The primary object of the invention is the provision of a generally improved fixture of this class which will be exceedingly simple in construction, cheap of manufacture, and efficient in use.

A further object is the provision of a more efficient fixture of this class which will not only increase the illuminating power of the fixture as a whole, but which will provide a field of illumination of great uniformity throughout, and particularly free of glare, shadows, and other objectionable features.

With this end in view, the invention relates particularly to an improved secondary or open double reflector comprising two oppositely extending connected or truncated conoidal reflectors having their constricted or truncated portions surrounding the source of illumination in substantially the same horizontal plane, said conoidal reflectors being arranged in co-operative relation to the source of illumination and the overhanging main or canopy reflector, and being particularly adapted for use in lieu of and as an improvement on the ordinary bowl-shaped secondary or pendant reflector now in common use in this class of lighting fixtures.

A still further object is the provision of an improved fixture of this class particularly designed and adapted for use in connection with a lamp bulb of the "nitrogen type" now in extensive use, and which not only gives a very intense light at its filament, but has an elongated bulb stem or shank, and with this end in view, my invention further relates to an improved hollow ventilated main

or canopy reflector, together with improved means for assembling and connecting the improved parts.

A still further object is the provision of an improved fixture of this class which is adapted not only to provide for a proper circulation of air about the lamp bulb to cool and prolong the life of the latter, but one which is particularly sanitary and safe in use, being particularly free from dust collecting openings or pockets, and at the same time presenting an ornamental and attractive outline and artistic appearance.

With the above mentioned and other ends in view, the invention consists in the novel construction, arrangement, and combination of parts, hereinafter described, illustrated in one of its embodiments in the accompanying drawings, and particularly pointed out in the appended claims.

Referring to the drawings, forming a part of this specification, Figure 1, is a vertical central sectional view of a lighting fixture constructed in accordance with this invention.

Fig. 2, a fragmentary sectional view of a slightly modified form of the improved secondary or open ended double reflector and showing the latter made of glass or vitreous material.

Similar numerals of reference designate like parts throughout all the figures of the drawings.

The main or canopy reflector 1, may be of any suitable and convenient form, but, in the present instance, is provided on its under side with an annular concaved portion 1^a, adapted to deflect the light rays downwardly and outwardly therefrom as received from the subjacent source of illumination and secondary reflector as hereinafter described. The main or canopy reflector may be suspended by means of a supporting thimble 2, the latter, in the present instance, being detachably secured to the top central portion of the canopy reflector by means of thumb screws 2^a, said supporting thimble 2, being adapted to surround or cover the lamp

- socket 3. The lamp socket 3, in the present instance, is provided with a lamp bulb 4, of the nitrogen type, and which therefore embodies a long or elongated neck portion 4^b.
5 As the light at the filament 4^b, is very intense, the usual reflector bowl of translucent material is suspended below the lamp bulb so as to prevent any direct rays from being projected directly downwardly and outwardly therefrom to come into contact with the eyes of any person or persons immediately below the lamp, but such pendant reflector bowls greatly impair the efficiency of the lamp because many of the direct rays 10 are obviously lost or diffused.
15 Referring now to the present or improved reflector it will be seen that the same comprises a concentrically mounted open double reflector made up of upper and lower truncated conoidal reflectors 5 and 5^a, respectively, the constricted or truncated portions of the reflectors 5 and 5^a, being joined to form a constricted or ray dividing angular portion 5^b, arranged substantially in the same horizontal plane with the filament 4^b, and preferably slightly above the central portion thereof, as shown. This arrangement permits the direct rays 6, from the filament to pass directly downwardly and outwardly unobstructed through the open portion of the reflector 5^a, and it will be obvious that the eyes of any occupant in the room being illuminated directly beneath such lamp are not likely to be reached by such substantially vertically extending rays, and any other rays extending at a greater or less acute angle such as the rays 6^a, will strike the curved sides of the reflector 5^a, and be reflected down as the reflected rays 6^b.
20 25 30 35 40 45 50 55 60
As a means of cutting out any glaring rays from the main or canopy reflector 1, and particularly as a means of intercepting and reflecting such direct lateral rays 6^c, emanating from and above the filament or light source 4^b, which would otherwise pass directly beyond and beneath the canopy reflector 1, the upper conical reflector 5 is provided, said reflector 5, being adapted to reflect such rays upwardly against the main or canopy reflector and to be reprojected by the latter as the rays 6^d, while still other rays 6^e, as shown reach the main or canopy reflector directly and are reflected by the latter downwardly and outwardly as indicated. It will be seen that the rays of light emanating from the filament or source of illumination 4^b, at a very acute angle pass upwardly and downwardly therefrom without striking the reflectors 5 and 5^a, while those emanating at less acute angles to the respective axial planes of such reflectors are caught and reprojected by the latter as shown and above explained.

The double or open ended secondary reflector may be suspended beneath the canopy 65 reflector 1, in any suitable and convenient manner, and, in the present instance, by means of link rods 7, provided with hooks 7^a, connected to the central depending conical portion 1^b, of the main reflector and provided at their outer-ends with thumb nuts 7^b, threaded thereon. 70

As a means of particularly adapting the improved fixture to a lamp bulb 4, of the nitrogen type, the canopy reflector 1, comprises a hollow double walled structure having central openings 1^c, to receive the neck portion 4^a, and spaced therefrom to form air circulating passages, and as a means of ventilating the chamber formed between the walls of the canopy reflector, the supporting thimble 2, is provided with outlet ports 2^b. 75 80

While I have shown the open ended double reflector as comprising two sheet metal conoidal reflectors 5 and 5^a, having their truncated portions connected to each other by means of a seam or joint to form the angular or reduced portion 5^b, as shown in Fig. 1, of the drawings, it will be apparent that these reflectors 5 and 5^a, may be made integral of glass or other suitable vitrious material as indicated in Fig. 2, of the drawings, and it will be understood that the interior surfaces of the reflectors 5 and 5^a, when made of metal are provided with a suitable refracting surface or coating, such for example as, white porcelain enamel, or the like, and so likewise as to the annular concaved portion 1^a, of the canopy reflector 1.

From the foregoing description, taken in connection with the accompanying drawings, the operation and advantages of my invention will be readily understood.

Having thus described one of the embodiments of my invention, what I claim and desire to secure by Letters Patent, is,—

1. A lighting fixture, comprising a canopy reflector, a light source, and upper and lower truncated open conoidal reflectors surrounding said light source, and having their light intercepting and refracting portions above and below the latter, respectively, said lower conoidal reflector intercepting light rays emanating from said light source at more than forty-five degrees to the common axial plane of said reflectors. 110 115

2. A lighting fixture, comprising a canopy reflector, a source of illumination, and oppositely extending open truncated conoidal reflectors having their truncated portions surrounding said source of illumination on substantially a common horizontal plane with the latter and intercepting and reflecting rays of light emanating therefrom which would otherwise pass beyond said canopy reflector.

flector or below at acute angles of more than forty-five degrees to the respective axial planes of said reflectors.

3. In a lighting fixture, a light source, a main reflector, and a double open ended secondary reflector embodying truncated conoids, one of said conoids intercepting all such rays of light emanating from and above said light source which would otherwise pass directly beneath said main reflector, and the

other intercepting such rays as extend in planes of approximately forty-five degrees and more to the common axial plane of said main and secondary reflectors.

In testimony whereof I have affixed my 15
signature in the presence of two witnesses.

WESLEY E. COCHRAAN.
